REFRIGERATOR AND CONTROL
MECHANISM THEREFOR

George A. Brace, Highland Park, Ill., assignor to
The Hoover Company, North Canton, Ohio, a
corporation of Ohio

Application January 21, 1948, Serial No. 3,475

14 Claims. (Cl. 62—5)

1

The present invention relates to refrigerating apparatuses and more particularly to a refrigerating apparatus of the dual intermittent absorption type and the mechanism for governing the operation thereof.

It is an object of the present invention to provide a control mechanism for an intermittent absorption refrigerating system which exercises all its control functions through the operation of a pilot valve.

It is a further object of the present invention to provide a control mechanism for an intermittent absorption refrigerating system which normally cycles the apparatus to produce refrigeration and which holds the apparatus in a non-functioning condition as long as the refrigeration demand is satisfied and then returns the apparatus to normal cycling condition.

It is a further object of the present invention to provide a control mechanism for an intermittent absorption refrigerating system which includes manually operable means for modifying the cycling control mechanism to render the apparatus inoperative and for returning the apparatus to the condition obtained prior to intervention of the manually operative means.

It is a further object of the present invention to provide a refrigeration control mechanism which simultaneously regulates the operation of the refrigerating mechanism and the efficacy of heat transfer conditions within the refrigerating chamber.

Other objects and advantages of the invention will become apparent as the description proceeds when taken in connection with the accompanying drawings in which:

Figure 1 is a schematic view illustrating the present invention;

Figure 2 is a view partly in section and partly diagrammatic illustrating the control mechanism forming the subject matter of the present invention; and

Figure 3 is a detailed view of part of the mechanism of Figure 2.

The refrigerating mechanism per se consists of two identical units of the intermittent absorption type. Only the left hand unit of Figure 1 will be described specifically. The right hand unit of Figure 1 is identical with the left hand unit, hence corresponding parts are provided with corresponding reference characters distinguished by the addition of a prime.

The refrigerating unit comprises a generator-absorber A which is preferably, but not necessarily, of the type which contains a dry salt

absorbent, such as strontium chloride, for a refrigerant, such as ammonia. The generator-absorber A is made up of three concentric chambers. The central chamber 11 is a products of combustion flue which is surrounded by an annular cooling jacket 10. An annular chamber 12 surrounds the cooling jacket 10 and constitutes the housing for the absorbing material. The absorbing material contained in the space 12 communicates with the condenser C through the conduit 13. The condenser C communicates with the evaporator structure E by a conduit 14. The condenser C comprises a plurality of finned tubes in which the refrigerant vapor is condensed. The heat of condensation of the refrigerant is rejected to cooling air flowing over the condenser tubes.

The evaporator E comprises a liquid receiving chamber 15 which receives refrigerant in the first instance from the condenser discharge conduit 14. The heat absorbing surfaces of the evaporator comprise a pair of vertically extending sinuous conduits 16 and 17 which receive refrigerant liquid in common from the liquid receiver 15 by way of the conduit 18 and open at their upper ends into the upper portion of the reservoir 15. The evaporator conduit 16 is an air cooling conduit and, as shown in Figure 2, is provided with air cooling fins 20.

A conduit 23 connects the upper portion of the cooling jacket 10 with a finned tubular air cooled condenser 22. This portion of the system is charged with a cooling medium such as methyl chloride. Cooling medium vapor condensed in the condenser 22 discharges into the reservoir 24. Cooling liquid is then conveyed from the reservoir 24 to the upper portion of the jacket 10 by a conduit 25. The conduit 25 comprises an upwardly facing U-shaped portion 26, a downwardly facing U-shaped portion 27, and an upwardly facing U-shaped portion 28 which connects to the upper portion of the cooling jacket 10. The reservoirs 24—24' are interconnected by a gas conduit 29 which joins the reservoirs above the level at which the condenser discharge conduits 30—30' terminate therein.

The bight portion of the downwardly facing U-shaped conduit section 27 is thermally bonded to a metallic bar 32 of high conductivity which extends through the entire length of the products of combustion flue 11 and terminates shortly therethin. The conduit 27 is not in the path of the products of combustion discharging from the flue 11 but is positioned laterally to one side thereof. This conduit receives heat through the

conducting element 32 which is normally heated simultaneously with the generator-absorber A in a manner to be described more fully hereinafter.

When heat is supplied to the generator-absorber A, heat is conducted by the element 32 to the conduit 27 to vaporize a portion of the cooling medium. Vapor formed in conduit section 27 fills the horizontal section of the conduit and a part of the downwardly extending legs thereof so as to form a vapor lock to prevent further flow of cooling medium from the reservoir 24 into the cooling jacket 10.

As shown in Figure 1, during the period of time when the vapor lock is operative to prevent circulation, liquid accumulates in the reservoir 24 to a depth sufficient to submerge the end of the conduit 30. If heat is applied to the generator-absorber A', for example, under the conditions illustrated in Figure 1, and the application of heat to the generator-absorber A is discontinued there will be a sudden increase in pressure in the cooling system associated with the generator-absorber A' which will be applied through the conduit 29 to the surface of the liquid in the reservoir 24. Due to the sealed condition of the lower end of the conduit 30 this will apply an excess pressure on one side of the vapor lock sufficient to unbalance the same and to cause it to collapse with great rapidity. This subject matter is described and claimed in the copending application of Curtis C. Coons, Serial Number 692,267, filed August 22, 1946, now Patent No. 2,513,148, dated June 27, 1950.

The generator-absorber A is heated by a combustible fuel burner, such as a gas burner, 40 positioned beneath the generator-absorber to discharge its products of combustion into the flue 11. An auxiliary gas burner 41 is positioned beneath the projecting end of the conducting element 32 to apply its flame directly onto this element for a purpose to be described herein-after. The burners 40-40' and 41-41' are arranged to be ignited by a flash tube pilot structure indicated generally at 43.

As shown in Figure 1, the gas supply conduit 45 supplies fuel to the flasher pilot through the by-pass conduit 46 and to a gas valve control housing 47.

Referring now to Figures 2 and 3, the control mechanism is developed in detail. The housing 47 is interiorly divided into three chambers 50, 51 and 52. The supply conduit 45 opens into the central chamber 50 which houses the valve port structures 53, 53' which are positioned to receive valve plug elements 54-54' respectively. The valve plug elements 54-54' are secured to flexible diaphragms 55-55' respectively which divide the housing 47 into the chambers 50-52 and 50-51 respectively. The elements 55-55' are described herein as diaphragms but as used herein and in the appended claims this term is intended to include other types of pressure responsive movable sealing devices such as a bellows or slideable pistons. Soft coil springs 56-56' urge the valve plugs 54-54' onto their seats. The flexible diaphragms are provided with restricted bleed ports 57-57' to admit gas from chamber 50 to chambers 51 and 52. The top of the housing 47 is formed as a pilot valve casing 59 which receives a slideable valve control element 60 provided with a single port 61.

The top wall of the chamber 52 is provided with a discharge port 63 controlled by the slide valve plate 60 and communicates with a gas

conduit 64 which, as shown in Figure 1, terminates adjacent the main burner 40. The left hand side of the casing 50, as viewed in Figure 2, is provided with a port 65 also controlled by the valve plate 60 which communicates with a gas conduit 66' which supplies gas to the burner 41'. The right hand end of the chamber 50 is provided with a port 67 communicating with a gas conduit 66 which supplies gas to the burner 41. The chamber 51 is provided with a port 68 communicating with a gas conduit 64' which terminates adjacent to the main burner 40'.

The valve structure 53-54 controls communication between chamber 50 and a gas conduit 70 which supplies gas to the burner 40. Similarly the valve structure 53'-54' controls communication between the chamber 50 and the conduit 71 which supplies gas to the burner 40'.

The pilot valve plate 60, shown in its extreme left hand position in Figure 2, extends beyond the housing 47 and terminates in an enlarged portion having a pin and slot connection 72 with a pivoted snap acting control lever 73 which is under the bias of a tension spring 74.

The arc of movement of the snap acting lever 73 is limited by the adjustable stops 76 which are carried by a control plate structure 77.

The lever 73 is actuated by a pair of pivotally mounted snap acting links 78-78' respectively which are connected by a link 79 for simultaneous operation. The linkage 78-78' is actuated by a spring 80 which is appreciably stronger than the snap spring 74 which operates the lever 73. The links 78-78' are arranged to be actuated by the opposed thermostatic bellows 81-81' respectively. The bellows 81-81' have their actuating bulbs 82-82' in contact with the absorber-generators A-A' respectively.

In the position of the apparatus illustrated in Figure 2 the bellows 81' is expanded to its full extent and has just operated the snap acting mechanism to the position shown thus shifting the opening 61 in the plate 60 into position to provide communication between the port 63 and conduit 64 to vent gas from the chamber 52 without resistance through the conduit 64 adjacent the burner 40. When chamber 52 is vented the excess gas pressure on the side of the diaphragm 55 facing chamber 50 overcomes the resistance of spring 56 and opens the valve port 53-54 allowing gas to flow through the conduit 70 to the burner 40 for heating the generator-absorber A. The bleed passageway 57 in the diaphragm 55 is so small that it allows only a very small quantity of gas to pass therethrough per unit of time, consequently a pressure differential in the chamber 50 is maintained over and above that prevailing in the chamber 52 by reason of the resistance to gas flow through the valve 54-53 and the usual spud or jet associated with the burner 40. By this construction the valve 53-54 is maintained in open condition as long as gas is allowed to vent freely from chamber 52 through the conduit 64. Gas discharged through conduit 64 is consumed in the flame of the burner 40.

As the generator-absorber A gradually heats, it eventually reaches some predetermined end point temperature at which the bellows 81 will expand to the right as viewed in Figure 2. As the bellows expands it will actuate the snap acting mechanism 78-78' over center against the bias of spring 80. As this mechanism snaps over center the lever 78 will strike the snap acting lever 73 and actuate the same to its extreme right hand position as viewed in Figure 2. This operation

will shift the valve plate 60 to seal the chamber 52 and to allow the chamber 51 to vent. As soon as chamber 52 is sealed the gas pressure in chambers 50 and 52 will quickly equalize through the bleed passageway 51 and the valve 53-54 will close thus de-energizing the burner 40. The chamber 51 is now allowed to vent which will open the valve 53-53' thus supplying gas through conduit 71 to the heater 40' for the generator-absorber A'.

The limits of movement of the snap acting mechanism 78-78' are determined by the fixed stops 83 and 83'.

The foregoing alternate operation of the control mechanism continues so long as there is a demand for refrigeration alternately heating and cooling the generator-absorbers A-A'. As soon as heat is applied to either generator-absorber heat conducted from the products of combustion discharged by the burners 40 or 40' quickly activates the vapor lock 27 or 27' associated with the generator-absorber being heated to interrupt and prevent further flow of the cooling medium into the cooling jacket of such generator-absorber.

The evaporator structure is positioned in the upper central portion of the cooling chamber of the cabinet with the inner section 17-17' of the evaporator positioned within an insulated housing structure 86 to refrigerate the same and its contents. The evaporator sections 16-16' and their associated fins 20-20' respectively are positioned laterally on opposite sides of the housing 86. An air directing casing 87 houses the entire evaporator structure to form air flues over the evaporator sections 16-16' and their associated fins. The bottom portion of casing 87 is slightly constricted as shown at 88 and air inlets are provided at 89 in the upper portion thereof so that air from the cabinet may enter through the openings 89, flow downwardly over the fins 20-20' and exit into the general food storage compartment through the constricted portion 88 of the housing 87. A plurality of air flow control valve plates 90 are pivotally mounted in the constricted throat 88 of the housing 87. The pivot pins of valve plates 90 are provided with actuating cranks 91 engaged in slots in a drive link 92 which is slidably mounted by any suitable means, not shown, on the housing 87. The drive link 92 is provided with a downwardly extending plate 93 which is urged to the left, as viewed in Figure 2, by a compression spring 94 against a thermostatic bellows 95. The bulb 96 of the bellows 95 is positioned in contact with one wall of the housing 87 in the path of the air stream rising upwardly in the food storage compartment so that the same responds to the temperature conditions obtaining in the food storage compartment of the refrigerator. The arrangement is such that expansion of the bellows 95 against the force of the spring 94 indicating a demand for refrigeration, moves the valve plates 90 into the full open position to allow maximum air flow across the air cooling evaporator structure 16-16'. When the air within the food storage compartment reaches a predetermined temperature such as 35 or 38° F. the bellows collapses and the bar 92 is advanced to the left as viewed in Figure 2 under the bias of spring 94 to move the plates 90 to the full closed position. By reason of this construction substantially uniform temperatures are maintained within the food storage compartment of the refrigerator without the risk of freezing the same and without placing limitations upon the lowest temperatures which may

be achieved within the insulated compartment 86.

The control plate element 77 slidably receives a U-shaped member 98 which is provided with downwardly extending stop lugs 99 and 99'. These stop lugs are biased by torsion springs into the downward position shown but are so mounted that they may swing inwardly toward each other against the bias of the torsion springs. The U-shaped member 98 is urged downwardly by a tension spring 100. When the member 98 is in its lowest position the elements 99 and 99' are in the path of movement of the snap link 73. If, for example, the snap link 73 is actuated from the position shown toward the right while the element 98 is in its lowest position it will ride by the lug 99 but will be brought to a dead stop by the lug element 99'. Thus the arm 73, under the conditions assumed will be brought to a stop in the dotted line position designated d. In this position of the apparatus the slide plate 60 will have aligned the port 61 with the port 67 and conduit 66 which will supply gas through the pipe 65 to the auxiliary burner 41. This burner will maintain the heat conductor 32 in a hot condition which in turn will maintain the vapor lock in the conduit 27 and will tend to maintain the temperature of the generator-absorber A without however heating the same to a degree sufficient to continue generation of refrigerant. The apparatus will remain in this condition until the supporting member 98 is raised to disengage the elements 73 and 99' at which point the element 73 will snap to its extreme right position against the stop 76 de-energizing the auxiliary heater 41 and energizing the main burner 40' of the generator-absorber A'.

The U-shaped member 98 is raised and lowered in accordance with the refrigeration demand by means of a cord mechanism actuated by the thermostat 95 against the bias of spring 94. This mechanism comprises a bell crank lever 102 pivotally mounted at 103 which is connected to the members 98 by a cord 104. The opposite arm of the bell crank lever is connected to the element 93 by a cord 105 passing around a guide pulley 106. When the element 93 moves to the right, as viewed in Figure 2, indicating a demand for refrigeration, slack is introduced into the cord 105 to permit the bell crank 102 to rotate in a counter-clockwise direction under the bias of the torsion spring 108 and to raise the member 98 to remove the stops 99-99' from the path of movement of the snap acting arm 73. In this condition the apparatus will cycle continuously under the control of the generator-absorber responsive thermostatic mechanism 81-81'. That is the snap mechanism will shift the valve plate 60 between its extreme positions to energize the burners 40-40' alternately. When the refrigeration demand is met the thermostat 95 will collapse and the element 94 will advance to the left, as viewed in Figure 2, and tension the cord 105 to rotate the bell crank 102 in a clockwise direction to allow the element 98 to drop into the path of movement of the element 73. When this occurs whichever part of the apparatus is then operating on a generating phase of operation will continue to do so until the generating period is completed whereupon the link 73 will be snapped over center by the thermostatic mechanism 81-81' and will come to rest in position a or d against the stop 99 or 99' respectively. This will de-energize burner 40 or 40' and will energize the burner 41 or 41' associated with whichever generator-absorber has just completed

its generating phase of operation to maintain the vapor lock and prevent a new absorbing cycle from initiating operation. At this time the other generator-absorber will have substantially completed its absorbing period of operation but it will continue to absorb such refrigerant, if any, as may remain in its associated evaporator system. When the apparatus again demands refrigeration the element 98 will be raised in the manner above explained and will permit the snap acting arm 73 to complete its arc of movement against one of the stops 76 under the influence of the spring 74 which will return the apparatus to normal cycling operation without being effected by the temperature control mechanism. The apparatus is thus returned to normal cycling operation with one generator-absorber fully charged with refrigerant and one generator-absorber fully discharged to begin adsorption and production of refrigeration immediately.

The apparatus also includes a mechanism for defrosting and shut-off purposes. This mechanism is shown in Figures 2 and 3 and comprises a manually operable dial 110 rotatably mounted on the front wall of the housing 87. A locking plate 111 is rigidly mounted with the dial 110 rearwardly of the front panel of the casing 87 and movable with the dial 110. Also rigidly secured to and movable with the dial 110 is a drum 112. One end of a cord 113 is secured to the periphery of the drum 112 to be wrapped around said drum when the dial 110 is rotated. The free end of the cord 113 is secured to a disk 114 to which a pair of cords 115 and 115' are secured. The cords 115 and 115' are anchored to the periphery of sector shaped drums 116 and 116', respectively, pivotally carried by the control plate 117. The drums 116-116' are integral with larger sector elements 117-117' which are provided with projecting peripheral flanges 118-118', respectively, extending across the plane of movement of the snap acting arm 73. In Figures 2 and 3 the dial 110 is shown in the "on" position of the apparatus with the arrow lying horizontally and pointing toward the left.

When the drum is rotated 90° clockwise so that the arrow points straight up a notch 120 in the disk 111 is rotated into engagement with a pivoted bell crank 121 pivoted on housing 87. The bell crank is biased into contact with the disk 111 by a torsion spring 122. When the notch 120 is brought into registry with the end of the bell crank 121 it engages the same and releasably locks the drum in the defrosting position. Movement of the dial 110 to the defrosting position tensions the cords 113, 115 and 115' and rotates the sectors 117-117' sufficiently to force the snap acting lever 73 into either of the dotted line positions *b-c* of Figure 2. That is, the sectors will move the lever 73 to a position closely adjacent its dead center position but lying on the side of the center position from which the movement of the lever started. When the arm 73 is in either of positions *b-c* of Figure 2 the port 61 will lie between the ports 65 and 67 of the chamber 50 and prevent flow of gas from that chamber through any of its exit ports. By this construction the entire apparatus is held in inoperative condition when the dial is turned to the defrosting mark.

The bell crank 121 has a forwardly projecting foot 124 which extends into the path of movement of the plate 93. As the temperature in the food cabinet warms up to a temperature such as 55° F., for example, the bellows 95 expands sufficiently

to force the plate 93 to the right a distance great enough to contact the projecting foot 124 of the bell crank and rotate the same in a counter-clockwise direction to release the engagement between the bell crank and the notch 120. When this occurs the torsion springs 125-125' bias the sectors 117-117', respectively, to their inactive positions against stop 126-126' and rotate the dial 110 and its associated parts back to the position shown in Figures 2 and 3.

If the dial 110 is rotated 180° in a clockwise direction so that the arrow of Figure 2 is horizontal but pointing to the right the notch 120 is brought into position to be engaged by a spring 15 pressed latch 127 which engages the notch to hold the drum 112 in fixed position.

The engagement between the bell crank 121 and notch 120 as well as the engagement between the notch 120 and the spring latch 127 is sufficient 20 to retain the drum 112 in fixed position against the bias of the springs 125-125', but it is insufficient to retain the drum in fixed position when the same is twisted by hand. The apparatus may be removed from "defrosting" condition or from the "off" condition by imparting a slight twisting motion to the dial to disengage the notch 120 from bell crank 121 or the latch 127 after which the springs 125-125' will complete movement of the dial and drum to the "on" position illustrated in Figure 2.

When the drum 112 is retained in the "off" position above explained the flanges 118-118' retain the snap lever at 73 in position *b* or *c* in the same manner in which this element is retained in those positions for defrosting operation. The sectors 117-117' rotate through a wider arc of movement when they operate in response to movement of the dial 110 to the "off" position, however the latter half of this arc of movement 35 does not alter the position of the lever 73. During this part of the movement of the sectors the surfaces 118 or 118' as the case might be simply slide in contact with the lever 73.

In accordance with the present invention the 40 control mechanism is required to operate only small gas bleeder valves to control both the main gas supply to the system and the cooling system. This feature permits the control mechanism to be constructed of comparatively small and light weight materials and to operate with a minimum of forces.

In accordance with the present invention the 45 operation of the apparatus is suspended at any time the demand for refrigeration is satisfied with the vapor lock maintained on the previously 50 heated generator so that immediately a new demand for refrigeration evidences itself a fully discharged generator will be available to produce the refrigerating effect in conjunction with an evaporator which then contains a complete charge of refrigerant.

While I have illustrated and described the 55 invention in considerable detail, it is to be understood that various changes may be made in the arrangement, proportion and construction of 60 parts without departing from the spirit of the invention or the scope of the appended claims.

1. In a refrigerating apparatus of the type 65 having a part which is alternately subjected to heating and cooling to cause operation of the apparatus, a gas burner arranged to heat said part, cooling means arranged to conduct a cooling medium in heat exchange relation with said part, said cooling means including a heat responsive portion for interrupting flow of cooling

medium to said part when heated and arranged to be heated when said heating means applies heat to said heated part, an auxiliary gas burner arranged to heat said heat responsive portion, means for supplying gas to said gas burners, cycling control means operating said gas supply means to supply gas to said first mentioned gas burner intermittently to heat said part and said heat responsive portion, and refrigeration demand responsive means for modifying the action of said cycling control means to supply gas to said auxiliary gas burner only to prevent cooling of said part when refrigeration demand is satisfied.

2. In an absorption refrigerating apparatus of the intermittent type which is alternately subjected to heat to generate refrigerant and cooled to produce a refrigerating effect, means for heating said apparatus, means for cooling said apparatus including a heat responsive part which discontinues the cooling effect when heated, said part being arranged to be heated simultaneously with said apparatus, a control mechanism responsive to a condition of said apparatus for activating and de-activating said heating means alternately, means for heating said part, and refrigeration demand responsive means for activating said last mentioned heating means to prevent cooling of said apparatus and the production of refrigeration when the refrigeration demand is satisfied.

3. Refrigerating apparatus of the absorption type comprising a pair of intermittent refrigerating units having parts which are alternately heated and cooled in out of phase relation to produce a refrigerating effect, means for heating and cooling said parts, control means for regulating the operation of said heating and cooling means including a member normally movable between two positions in each of which one of said parts is heated and another of which is cooled, refrigeration demand responsive means including a part which moves into the path of movement of said member to arrest movement thereof short of one of said positions to discontinue heating all of said parts, and manually operated means for moving said member to a position in which said heating means are inoperative independently of the operation of said refrigeration demand responsive means.

4. In a refrigerating apparatus of the absorption type having a cooling unit and a part which is alternately heated and cooled, a gas burner for heating said part, means for cooling said part, a chamber for receiving gas under pressure from a source of supply, means for conducting gas from said chamber to said gas burner including a gas valve biased to closed position, a diaphragm having one side subjected to the pressure in said chamber and connected to operate said valve to open position when responding to said pressure, a chamber facing the other side of said diaphragm, means forming a bleed passage to permit gas under pressure to flow into said second mentioned chamber whereby the pressure is equalized on both sides of said diaphragm, an exhaust port for discharging gas from said second mentioned chamber at a rate greater than the rate at which gas enters said chamber through said bleed passage, a valve for controlling said exhaust port and control means for operating said second mentioned valve for controlling said gas burner.

5. In a refrigerator, a pair of intermittent absorption refrigerating units, a pair of gas burners

each of which is arranged to heat one of said units, cooling means for said units including parts associated with each unit arranged when heated to prevent cooling of the associated unit, control means comprising a pair of gas valves biased to closed position, each of said gas valves being arranged to control the flow of gas to one of said burners, a pair of pressure responsive means each connected to operate one of said gas valves, means for subjecting each of said pressure responsive means to gas under pressure in a manner tending to operate said pressure responsive means to open said gas valves, by pass means for subjecting said pressure responsive means to said gas under pressure in a manner tending to operate said pressure responsive means to close said gas valves, a pair of venting means for relieving said pressure responsive means of gas under pressure tending to operate said pressure responsive means to close said gas valves, and cycling control means operable to open said venting means successively to supply gas to said gas burners successively.

6. Refrigerating apparatus including a pair of intermittent absorption refrigerating systems of the type which are successively heated and cooled in operation, means for heating said systems, means for cooling said systems including heat responsive means arranged to be heated simultaneously with said systems and operable to discontinue cooling of the systems being heated, means for governing the operation of said heating and cooling means, thermostatic cycling control means responsive to the thermal condition of portions of said systems for operating said governing means to heat and cool each of said systems successively and in out of phase relation with each other, refrigeration demand responsive means for modifying the operation of said cycling control means when the refrigeration demand is satisfied to prevent said cycling control means from operating said governing means to heat the refrigerating system normally next to be heated by said heating means, and means operative to heat said heat responsive means to prevent cooling of the previously heated refrigerating system when said refrigeration demand responsive means operates to modify said cycling control means.

7. Refrigerating apparatus including a pair of intermittent refrigerating systems of the type which are successively heated and cooled in operation each including a heating means, a cooling means having a heat responsive part arranged to be heated simultaneously with the system and operative when heated to prevent cooling of the system, and an auxiliary heating means arranged to heat said heat responsive part, control means comprising means responsive to a condition of the system for activating said heating means successively, refrigeration demand responsive means for modifying the operation of said control means to de-activate both said heating means and to activate the auxiliary heating means associated with the previously heated system as long as refrigeration demand is satisfied.

8. Refrigerating apparatus including a pair of intermittent refrigerating systems of the type which are successively heated and cooled in operation each including a heating means, a cooling means having a heat responsive part arranged to be heated simultaneously with the system and operative when heated to prevent cooling of the system, and an auxiliary heating means arranged to heat said heat responsive part, control means comprising means responsive to a condition of

11

the system for activating said heating means successively, refrigeration demand responsive means for modifying the operation of said control means to de-activate both said heating means and to activate the auxiliary heating means of the previously heated system as long as refrigeration demand is satisfied and manually operable means de-activating all of said heating means.

9. Refrigerating apparatus including a pair of intermittent refrigerating systems of the type which are successively heated and cooled in operation each including a heating means, a cooling means having a heat responsive part arranged to be heated simultaneously with the system and operative when heated to prevent cooling of the system, and an auxiliary heating means arranged to heat said heat responsive part; control means comprising means responsive to a condition of the system for activating said heating means successively, refrigeration demand responsive means for modifying the operation of said control means to de-activate both said heating means and to activate the auxiliary heating means of the previously heated system as long as refrigeration demand is satisfied and manually operable means for modifying the operation of said control means to de-activate all of said heating means, and means operated by said refrigeration demand responsive means responding to an abnormal temperature condition for operating said manually operable means to a position in which it is ineffective to modify the operation of said control means.

10. Refrigerating apparatus comprising a pair of intermittent absorption refrigerating systems each including a generator-absorber, a condenser, and an evaporator connected in circuit; a heater associated with each of said generator-absorbers, control means for said heaters including a part movable between two control positions in each of which one of said heaters is activated to heat its associated generator-absorber, thermostatic means responsive to the thermal condition of said generator-absorbers for operating said part between said positions to heat said generator-absorbers alternately, refrigeration control means operative in response to satisfaction of refrigeration demand to arrest movement of said part in a position in which neither of said heaters is activated, manually settable means operative to shift said part to a position in which neither of said heaters is activated, and means operated by said refrigeration control means responding to a defrosted condition of said evaporators for releasing said part from restraint by said manually settable means.

11. Refrigerating apparatus of the absorption type comprising a pair of intermittent refrigerating units having parts which are alternately heated and cooled in out of phase relation to produce a refrigerating effect, means for heating and cooling said parts, said cooling means including means associated with each of said parts and arranged to be heated therewith operative when heated to prevent cooling of its associated part, means arranged to heat each of said last mentioned means independently, control means for governing the operation of all of said heating means including a member normally movable between two positions in each of which one of said parts is heated and the other of said parts is cooled, refrigeration demand responsive means including an element which moves into the path of movement of said member to arrest movement thereof between said positions in which said

12

control means activates whichever of said second mentioned heating means is associated with the part previously heated, and manually operated means for moving said member to another position in which all of said heating means are inactive independently of the position of said refrigeration demand responsive means.

12. A refrigerating apparatus of the absorption type having a cooling unit and a part which is alternately heated and cooled, a gas burner for heating said part, heat operated means arranged to be heated simultaneously with said part for rendering said cooling means inoperative when heated, an auxiliary gas burner for heating said heat operated means, means for cooling said part, a chamber for receiving gas under pressure from a source of supply, means for conducting gas from said chamber to said gas burner including a gas valve biased to closed position, a diaphragm having one side subjected to the pressure in said chamber and connected to operate said valve to open position when responding to said pressure, a second chamber facing the other side of said diaphragm, means forming a bleed passage to permit gas under pressure to flow into said second chamber whereby the pressure is equalized on both sides of said diaphragm, an exhaust port for discharging gas from said second chamber at a rate greater than the rate at which gas enters said second chamber through said bleed passage, a valve for controlling said exhaust port, control means for operating said second mentioned valve for controlling said gas burner, and means operable to supply gas to said auxiliary gas burner through said second mentioned valve when it is in a position to close said port.

13. Refrigerating apparatus including a pair of intermittent absorption refrigerating systems each including a part which is successively heated and cooled in operation, means for heating and cooling said parts, means for governing the operation of said heating and cooling means, thermostatic cycling control means responsive to the thermal condition of said parts of said systems for operating said governing means to heat and cool each of said parts successively and in out of phase relation with each other, refrigeration demand responsive means operative when refrigeration demand is satisfied to bar operation of said governing means by said cycling control means to apply heat to whichever of said parts is being cooled when refrigeration demand is satisfied, and manually operable means for operating said governing means to terminate heating and cooling of said parts independently of the action of said refrigeration demand responsive means and said cycling control means.

14. Refrigerating apparatus including a pair of intermittent absorption refrigerating systems each including a part which is successively heated and cooled in operation, means for heating and cooling said parts, means for governing the operation of said heating and cooling means, thermostatic cycling control means responsive to the thermal condition of said parts of said systems for operating said governing means to heat and cool each of said parts successively and in out of phase relation with each other, refrigeration demand responsive means operative when refrigeration demand is satisfied to bar operation of said governing means by said cycling control means to apply heat to whichever of said parts is being cooled when refrigeration demand is satisfied, manually actuated means movable from

an inoperative position to an operative position for operating said governing means to terminate heating of said both of said parts independently of the action of said refrigeration demand control means and said cycling control means, means biasing said manually actuated means to said inoperative position, releasable means for retaining said manually actuated means in said operative position and means operated by said refrigeration demand responsive means for releasing said releasable means when said responsive means responds to a defrosting temperature condition.

GEO. A. BRACE.
